(57) **CLAIM**

The ornamental design for a camera as shown and described herein.

DESCRIPTION

FIG. 1 is a top, front and left side perspective view of a camera showing the new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevation view thereof; and,

FIG. 7 is a back elevation view thereof.

The broken lines depict portions of the camera that form no part of the claimed design.
